RAYMOND A. KLINE, OF NEW YORK, N. Y.

SHOW-CASE DISPLAY-TRAY.

1,289,193.

Specification of Letters Patent. Patented Dec. 31, 1918.

Application filed March 15, 1917. Serial No. 154,920.

To all whom it may concern:

Be it known that I, RAYMOND A. KLINE, a citizen of the United States, residing in the city of New York, borough of Manhattan, county and State of New York, have invented a certain new and useful Show-Case Display-Tray, of which the following is a specification.

This invention is a display tray adapted to 10 rest on top of a show-case to facilitate the exhibition and handling of jewelry, silverware, and other articles.

In the sale of jewelry and various other articles, it is quite common to remove the 15 articles from the interior of show-cases, safes, etc., and lay them upon the glass tops of such show-cases, for a more close inspection by the prospective purchaser. To obviate the objection of marring the glass tops 20 of the show-cases or the jewelry laid thereupon, as well as to preclude rattling when the articles are moved about, it has been the practice to dispose small pads of felt, velvet, or other loose material, on top of such cases 25 so that the jewelry, when taken from the case, may be laid upon said pads without noise and without fear of marring either the case or the articles. The loose pads referred to cannot be handled to good ad- 30 vantage, and, what is particularly objectionable, they present an unsightly and unattractive appearance after they have been used for even a comparatively short time.

Moreover, it is recognized that various 35 articles, particularly jewelry, show up to better advantage on a background of a particular color, while other articles will be enhanced by their exhibition on a background of some other appropriate, distinctive color.

40 A fundamental consideration in the sale of articles of this character is the esthetic effect and beauty which the articles present. Accordingly, it is vitally important to provide means whereby the various colors best 45 adapted for this purpose may be expeditiously availed of. It is, moreover, frequently desirable to lift the background from the top of the show-case and tilt up the same, so that the prospective purchaser 50 may better see the beauty of the article when viewed from a distance, and, yet, without disturbing the relative arrangements of the different articles on the tray. The show-case pads heretofore employed for this purpose 55 have been of a flexible nature, which ren-

dered them extremely difficult to handle when lifted from the show-case, particularly when comparatively heavy articles were positioned thereon, said pads becoming bent or curved when so handled, whereby the beauty 60 and effect of the articles, when viewed, as they properly should be, upon a flat surface, were lost.

With the foregoing considerations in mind, the object of the present invention is 65 to provide a show-case display tray which will embody all the advantages, and others, of the prior devices, and be devoid of their disadvantages; moreover, one which will embody a plurality of colors, any one of 70 which may be employed as a background, as the particular article to be exhibited may require.

A further object of the invention is to provide a display tray having a soft, yield- 75 able surface on which the articles may be placed, but which, in its entirety, is of such rigid nature that it may be readily handled, when free from engagement with the show-case, without fear of bending or folding the 80 device, with consequent danger of the articles being displaced and falling therefrom.

Features of the invention, other than those specified, as well as the advantages thereof, 85 will be apparent from the hereinafter detailed description taken in conjunction with the accompanying drawing.

In the accompanying drawing I have illustrated one practical embodiment of the invention, but the construction therein shown 90 is to be understood as illustrative, only, and not as defining the limits of the invention.

Figure 1 is a perspective view of a show-case display tray constructed in accordance 95 with the present invention.

Fig. 2 is a transverse section taken on line 2—2 of Fig. 1, and

Fig. 3 is a perspective detail of a certain cushion which is employed, showing the same partly in section and partly in elevation in 100 the interest of clearness.

Referring to the drawing, A designates a supporting base which may be of any desired shape or contour, but is, preferably, in the form of a rectangular plate, the outer edges of which are beveled or fluted to render the same more esthetic in appearance. The upper face of base A is provided with a depression a, which forms a pocket 105 in which may be seated a cushion B, on 110

which the articles to be exhibited may be placed without danger of marring the same, and to the exclusion of noise.

The construction of cushion B is best shown in Figs. 2 and 3. In its preferred form, the cushion B embodies two sheets of cardboard or veneer, C C', which are glued or otherwise adhesively secured together, with the free edges of two lengths of fabric, 10 c c', which are stretched over the outer surfaces of the sheets C C', respectively, interposed between them, as clearly shown in Fig. 3. The fabric lengths C C' are, preferably, of different colors, so that the opposite 15 faces of the cushion are correspondingly colored, *e. g.*, red and brown.

The cushion is of such dimensions and contour as to readily occupy the depressed seat *a* of the base A, which serves as a support therefor. Cushion B fits loosely into the depression *a* from which it may be expeditiously removed and replaced, with either side of the cushion exposed, according to the particular color which it is desired to 25 employ in displaying articles on the tray.

It is well known that certain articles, such as pearls, diamonds, and platinum, appear to better advantage on a background of one color than another, as is also the case with 30 gold, silver, cut-glass, etc. Accordingly, the salesman is enabled, through the use of the display tray of this invention, to obtain the more appropriate color by manipulation of the cushion B as described.

35 The supporting of the cushion on the rigid base A allows of ease in handling the tray, without fear of the buckling or bending of the cushion, with consequent danger of spilling the articles therefrom. Moreover, that portion of the base which is visible beyond the edges of the cushion appears as a beveled border and imparts a finished and esthetic appearance to the tray.

To facilitate the shifting or sliding of 45 the tray over the glass top of a show-case, the base A is, preferably, provided, on its under side, with a supporting bead *a'*, positioned adjacent the edges of the tray, and of such dimensions as to elevate the base A 50 a slight distance above the supporting surface. This slight elevation allows the tray to be more readily lifted from a flat surface, such as a show-case top, since the salesman may insert his finger-tips beneath the edges 55 of the tray to grasp the same, preparatory to picking it up.

It will be manifest, from the foregoing description of the preferred practical embodiment of the invention, that the tray is a 60 marked improvement over those makeshifts of the prior art, the deficiencies of which it is the object of the invention to supply. A tray results which may be used with maximum efficiency in the accomplishment of the 65 results desired, among which are manifest

ease and dexterity in exhibiting the articles to be displayed, as well as the showing of such articles to the best advantage. Moreover, the tray of this invention is simple in construction, economical to manufacture, 70 durable in use, does not unduly encumber the show-case, and is, in fact, an ornament thereto.

Aside from the uses referred to, the present invention may be employed with great 75 efficiency as a permanent show-case display tray *i. e.*, one which is "dressed" in the morning, usually with novelties, and adapted to remain in such condition throughout the day on the top of a show-case until the 80 articles are removed therefrom at the close of business. When so employed, as well as employed in the manner hereinbefore described, the elevating of the tray base member A by the supporting bead *a'* above the 85 glass top of the show-case allows the tray to readily slide over the supporting surface with the edges of said tray free from engagement therewith. By this construction dust or lint does not gather on the supporting surface along the edges of the tray when the same is shifted, as would be the case if the base A rested directly upon the show-case. The edges of the tray are thus maintained free from dust and in a cleanly, neat 90 condition.

Moreover, by having the pad B removable its edges may be readily dusted, and dust cannot accumulate in the cracks adjacent the edges of said pad to produce untidy effects. 100

Having thus fully described the invention, what I claim as new, and desire to secure by Letters Patent, is:

1. A show-case display tray for exhibiting jewelry, adapted to rest horizontally on the 105 bottom of the show-case, or on the top thereof, embodying a rigid base member, provided in its upper or exposed face with a depressed seat surrounded by an upper marginal edge beveled outwardly, a bead positioned on the under side of said base member and near the periphery thereof for elevating said base member above the supporting surface on which the tray is supported, whereby the tray may be readily grasped at 110 its edges, with the fingers beneath the same, and readily lifted from its supporting surface, as well as moved around thereon, without undue friction, in combination with a substantially flat cushion loosely positioned 115 within the said depressed seat, said cushion embodying a foundation member having a fabric of one color attached to one face thereof, and a fabric of a contrasting color attached to the other face thereof, whereby 120 the cushion may be positioned in the seat with that side of the cushion exposed whose color forms the more harmonizing background for the jewelry to be exhibited thereon.

2. A show-case display tray for exhibiting jewelry, embodying a rigid base member provided, in its upper face, with a depressed seat, a substantially flat cushion loosely positioned in said seat, said cushion embodying two sheets of rigid material adhesively secured together in lapping relation, a length of fabric of one color stretched over the exposed face of one of said sheets, and a length of fabric of a distinctly different color stretched over the exposed face of the other of said sheets, with the edges of the fabric lengths adhesively secured between the inner edges of said sheets, whereby the cushion may be positioned in the seat of the base, and be reversible therein, whereby that side of the cushion which best harmonizes with the jewelry to be exhibited on the cushion, may be exposed.

3. A show-case display tray for exhibiting

jewelry, adapted to rest horizontally on the bottom of the show-case, or on the top thereof, embodying a rigid base member provided, in its upper face, with a depressed seat of such extent as to provide a border 25 frame on the upper face of said base member, and a substantially flat cushion, loosely positioned in the depressed seat, with the upper face of the cushion substantially flush with the upper edge of the border frame, 30 said cushion being reversible and having its opposite faces, respectively, of pronouncedly different colors, whereby the cushion may be positioned within the seat of the base member, with that face thereof exposed whose 35 color forms the more harmonizing background for the jewelry to be exhibited.

In testimony whereof I have signed my name to this specification.

RAYMOND A. KLINE.
